ATTORNEYS

UNITED STATES PATENT OFFICE.

JACOB E. BASHORE AND CHARLES W. JENSEN, OF TIPPECANOE CITY, OHIO.

VICE.

No. 918,946.

Specification of Letters Patent.

Patented April 20, 1909.

Application filed October 6, 1908. Serial No. 456,450.

To all whom it may concern.

Be it known that we, JACOB E. BASHORE and CHARLES W. JENSEN, citizens of the United States, residing at Tippecanoe City, 5 in the county of Miami and State of Ohio, have invented a new and useful Improvement in Vises, of which the following is a specification.

Our invention relates to improvements in 10 vises and has for its object to produce a vise in which a movable jaw may be quickly adjusted by hand toward or from a fixed jaw, according to the thickness of the work to be grasped, and then secured and caused to move 15 slightly toward said fixed jaw by the turning of a handle bar or lever.

Our invention therefore consists in certain 20 novel features of construction, arrangement and combination of parts, as will be herein- 25 after fully described and pointed out in the claims, reference being had to the accompanying drawings in which—

Figure 1 is a vertical section of a vise and 30 frame showing our improvements. Fig. 2 is 25 a horizontal section of the vise frame showing the operative parts of the vise in plan. Fig. 3 is a perspective view of the cam. Fig. 4 is a face view of the clamp plate.

1 is the fixed jaw of the vise which is shown 35 30 as the frame work of a bench, and 2 is the movable jaw.

Extending from the fixed jaw 1 to the back 40 bar 15 of the bench and rigidly connected at 35 both ends, are the two clamp bars 9, 9 placed side by side and separated a suitable distance; 45 these two clamp bars are square in cross section and support a clamp member 7 which has square notches 7^a in each vertical side in which lie the clamp bars 9, and which has 50 also circular openings 7^b near its upper and lower ends through which pass the round 55 pulling bars 8, the rear ends of said bars 8 being threaded to receive the nuts 12 which are screwed on the bars 8 on either side of the 60 clamp plate 7 when placed in position; the 55 front ends of the bars 8 are bent to form hooks 8^a the inner surfaces of the hooks being curved. The bars 8 pass through the rigid 65 jaw of the vise and also through the movable 70 jaw 2 and the front hooked ends engage a 75 spiral cam 5 which has a central opening 5^a therethrough and a flat channel 5^b in its front 80 face. The cam 5 is fitted on a circular boss 6^a on the center plate 6 which is secured to 85 55 the movable jaw 2 by screws and has the rectangular openings 6^b through which pass the

hooked ends of the pulling rods 8. Over the cam 5 and the center plate 6 is secured the cover 4, said cover having a central aperture to allow the cam 5 to pass through it, said 60 cam being held to the center plate by a bolt 13 which passes through the boss 6^a and is secured by a nut 16 on the inner end of the bolt; this bolt also holds in place a handle 10 which is flattened at its center and cut out 65 and fits in the channel 5^b in the outer face of the cam 5; on each end of the handle 10 is a knob 11. As stated the pulling bars 8 have 70 hooked ends which engage the spiral cam 5, the hooks fitting on the spiral rib 5^c, of the 75 cam. The circular openings 7^b, through the clamp plate are slightly larger than the diameter of the threaded ends of the pulling rods 8 to allow the clamp plate to cant 75

The operation of the vise is as follows. The handle 10 is swung around until the pulling rods move the clamp plate to a vertical position when the horizontal walls of the rectangular notches 7^a will be parallel with 80 the upper and lower faces of the clamp bars 9, 9; the movable jaw may now be moved toward the fixed jaw until it engages the article to be clamped; the handle 10 is then 85 swung farther around carrying the cam with it and the pulling rods 8, 8, causing the clamp plate 7 to assume the position shown in Figs. 1 and 2, whereupon the horizontal faces of the rectangular notches 7^a being canted obliquely to the upper and lower faces of the 90 clamp bars 9, clamp or grip the same and consequently hold the movable jaw of the vise tightly against the article in the vise. As the pitch of the spiral rib 5^c on the cam is 95 rapid the vise will be very quick acting both in applying and releasing.

The operative parts are mostly out of sight and the cam being covered by the housing 4 will be protected from dust and grease.

We claim—

1. In a vise the combination with a fixed jaw and frame, rigid clamp bars held in said frame, of a movable jaw, pulling rods slidably supported in the fixed jaw and frame and supporting the movable jaw, a clamp plate carried by said pulling rods and recessed to slide on the clamp bars when in plane at right angles to the clamp bars, and a rotatable cam carried by the movable jaw and engaging the pulling rods to cant the 105 clamp plate and cause its recessed portion to grip the clamp bars. 110

2. In a vise the combination with a fixed jaw and frame, rigid clamp bars held in said frame, of a movable jaw, a rotatable cam carried by said movable jaw, pulling rods 5 engaging said cam and longitudinally movable thereby, said pulling rods passing through the movable and fixed jaws, a clamp plate tiltably supported on said rods and having notches in its said edges adapted to 10 slidably engage the clamp bars.
3. In a vise the combination with a fixed jaw and frame, rigid clamp bars held in said frame, of a movable jaw, a rotatable cam carried by said movable jaw, pulling rods 15 engaging said cam and longitudinally movable thereby, said pulling rods passing through the movable and fixed jaws, and a tilttable clamp plate adjustably held on said pulling rods and having notches in its side edges adapted to slidably move on the clamp bars and to grip the same when canted from 20 a plane perpendicular to the clamp bars.
4. In a vise the combination with a fixed jaw and frame, rigid clamp bars held in said frame, of a movable jaw, a rotatable spiral cam mounted thereon, pulling rods having hooked ends engaging the spiral cam, and passing through the movable and fixed jaws, a clamp plate adjustably carried by said pulling rods and having recesses adapted to 25 slidably move on said clamp bars when held in a plane perpendicular to that of the clamp bars, and to grip the said clamp bars when tilted by the pulling rods through the agency 30 of the spiral cam.
5. In a vise the combination with a fixed jaw and frame, rigid clamp bars held in said frame, of a movable jaw, a rotatable cam carried by said movable jaw, pulling rods 35 engaging said cam and longitudinally mov-
- able thereby, a housing secured to the movable jaw and protecting said cam, the pulling rods passing through the movable and fixed jaws, a clamp plate tiltably supported on said rods and having openings adapted to 40 slidably engage the clamp bars.
6. In a vise the combination with a fixed jaw and frame, rigid clamp bars held in said frame, of a movable jaw, a centering stud mounted on the outer face of said movable jaw, a spiral cam rotatably mounted on said centering stud, pulling rods having notched ends engaging said spiral cam, and passing through the movable and fixed jaws, a clamp plate tiltably supported on said rods and having openings adapted to 45 slidably engage the clamp bars.
7. In a vise the combination with a fixed jaw and frame, rigid clamp bars held in said frame, of a movable jaw, a centering stud mounted on the outer face of said movable jaw, a spiral cam rotatably mounted on said centering stud, pulling rods having hooked ends engaging said spiral cam and passing through the movable and fixed jaws, a housing secured to the movable jaw and inclosing the spiral cam, a clamp plate tiltably carried by said pulling rods and having recesses adapted to 50 slidably move on said clamp bars when held in a plane perpendicular to that of the clamp bars, and to grip said clamp bars when tilted by the pulling rods.
